UNITED STATES PATENT OFFICE.

SAMUEL MORRIS, OF NEWARK, OHIO, ASSIGNOR OF ONE-HALF TO MOSES H. NEIL, OF COLUMBUS, OHIO.

CAR-COUPING.

SPECIFICATION forming part of Letters Patent No. 746,728, dated December 15, 1903.

Application filed July 25, 1903. Serial No. 167,015. (No model.)

To all whom it may concern:

Be it known that I, SAMUEL MORRIS, a citizen of the United States, residing at Newark, in the county of Licking and State of Ohio, have invented certain new and useful Improvements in Car-Couplings; and I do hereby declare the following to be a full, clear, and exact description of the invention, such as will enable others skilled in the art to which it applies to make and use the same.

The object of this invention is to provide an improved automatic coupling of simple and economical construction adapted to effect the coupling of cars as well upon curved as upon straight tracks.

The invention is embodied in the construction herein shown and described, the particular features of novelty being pointed out in the claims.

In the accompanying drawings, illustrating one form of the invention, Figure 1 is a front elevation with the knuckle removed. Fig. 2 is a sectional view horizontally of the draw-bar, the knuckle being in full plan view. Fig. 3 is a perspective view of the knuckle. Fig. 4 is a perspective view of the pin. - Fig. 5 is a plan illustrating the position of the knuckle in the draw-head when the cars are coupled on a curved track. Fig. 6 shows a plan depicting the position of the knuckle when the cars are coupled on a straight track. Figs. 7 and 8 are front views, the former showing the position of the pin when the cars are coupled on a curved track and the latter when on a straight track.

Like characters of reference in the several views designate corresponding parts.

1 designates the draw-bar, and 2 the knuckle, pivoted on a pin 2^f in the draw-head, as usual. The knuckle viewed horizontally has a wedge-shaped arm 2^a and a finger 2^b extending angularly inward from the arm 2^a, said finger to reach behind shoulders 1^a back of the main cavity of the draw-head. The arm 2^a has at its corner on the outward side a locking edge 2^d. This arm is also notched, as indicated, at the upper end of this corner to form a locking edge 2^c and a seat or shoulder 2^e for the locking-pin, as hereinafter set forth. The edge 2^d is located forward of the edge 2^c.

3 designates a spring, secured in the cavity

of the draw-head behind the knuckle, tending to throw the arm 2^a and the knuckle outward to uncoupled position.

4 designates the locking-pin. This pin is 55 cut away, as indicated, to form two horizontal shoulders 4^a and 4^b, the shoulder 4^b being located higher on the pin than the shoulder 4^a. Between these shoulders is a vertical knuckle-locking edge 4^c. The pin 4 works 60 vertically but non-rotatively in a hole 5 in the draw-head adjacent the path of movement of the end of the arm 2^a and finger 2^b, and the pin is operated in its downward movement by gravity or, if desired, by a spring 65 (not shown) and in its upward movement by hand.

The operation is as follows: In uncoupled position the pin is constantly supported on the upper face of the finger 2^b by the resting 70 of the shoulder 4^a thereon. When the finger 2^b is thrown in by an approaching coupler, the pin falls and the locking edge 4^c thereof engages the edge 2^c of the arm 2^a, the shoulder 4^a resting on the seat 2^e. This 75 engagement of the locking edges, as just described, will couple the cars on a curve and the knuckle will be in the position indicated in Figs. 5 and 7, and when the cars run onto a straight track the finger 2^b will be forced 80 farther in by the straightening of the cars with respect to each other and the locking-pin will drop until the locking edge 4^c thereof engages the corner 2^d or locking edge of the arm 2^a. When uncoupled cars are run together on a straight track, the locking-pin 85 of course falls at once to the position where the locking edge 4^c engages the corner or locking edge 2^d.

In the construction shown the pin in its 90 downward movement is first supported by the resting of the shoulder 4^a on the shoulder 2^e and then by the resting of the shoulder 4^a on the floor of the draw-head; but this is not the only way in which the operation may 95 take place, because the locking edge 4^c between the shoulders can be made shorter and the pin supported by the shoulder 4^b on the shoulder 2^e. The construction shown, however, is preferred because it gives a good 100 locking edge 4^c.

Should the pivot-pin 2^f of the knuckle be

accidentally cut off because of the heaviness of the load, or should that pin be lost while the cars are coupled the cars will still remain coupled because of the engagement of the 5 finger 2^b with the shoulders 1^a conjointly with the engagement of the locking-pin 4 with the arm of the knuckle.

What I claim, and desire to secure by Letters Patent, is—

- 10 1. The combination in a car-coupling of a pivoted knuckle having an arm with two locking edges, one forward of the other, a spring tending to hold said arm outward, and a locking-pin having shoulders 4^a and 4^b and 15 a locking edge 4^c between said shoulders to engage the locking edges on the aforesaid arm automatically and successively.
2. The combination in a car-coupling of a

pivoted knuckle having an arm with two locking edges, one forward of the other and 20 a finger projecting inward from said arm adapted to support a locking-pin in the open position of the knuckle, a spring tending to hold said knuckle in open position, and a locking-pin adapted to be supported by the 25 aforesaid finger and having a locking edge adapted to automatically and successively engage the locking edges of the aforesaid arm.

In testimony whereof I affix my signature 30 in presence of two witnesses.

SAMUEL MORRIS.
